Primary Examiner — Jack Reickel*Assistant Examiner* — Christopher M Spivey(74) *Attorney, Agent, or Firm* — ScienBiziP, P.C.(57) **CLAIM**

The ornamental design for a display screen with icon, as shown and described.

DESCRIPTION

FIG. 1 is a detail or enlargement of the design of a display screen with icon of FIG. 2; and,
 FIG. 2 is a front view of a display screen with icon.
 The broken line showing of a display screen is for the purpose of illustrating portions of the article and forms no part of the claimed design.
